FREDRICK WINTERHALTER AND FREDRICK T. WINTERHALTER, OF BAYONNE, NEW JERSEY.

PAPER-ROLL RACK.

1,261,668.

Specification of Letters Patent.

Patented Apr. 2, 1918.

Application filed February 7, 1917. Serial No. 147,077.

To all whom it may concern:

Be it known that we, FREDRICK WINTERHALTER and FREDRICK T. WINTERHALTER, citizens of the United States, and residents 5 of Bayonne, in the county of Hudson and State of New Jersey, have invented a new and Improved Paper-Roll Rack, of which the following is a full, clear, and exact description.

10 Our invention relate to paper-roll racks of the class utilized for dispensing wrapping paper for merchandise of various kinds.

An object of the invention is to provide a 15 simple, strong and inexpensive rack which will always present a portion of the paper from the roll ahead of the cutting knife, thus obviating the necessity of manipulating the roll of paper when paper is to be drawn from the roll.

20 Another object of the invention is to provide a paper-roll rack having feeding rollers whereby any desired quantity of paper may be fed from the rack without pulling on the end, extending in front or ahead of the 25 cutter.

With the above and other objects in view, the nature of which will more fully appear as the description proceeds, the invention 30 consists in the novel construction, combination and arrangement of parts as herein fully described, illustrated and claimed.

In the accompanying drawings, forming part of the application, similar characters of reference indicate corresponding parts in 35 both views.

Figure 1 is a perspective view of the paper-roll rack embodying our invention; and

Fig. 2 is a vertical cross section therethrough.

40 The racks commonly employed for dispensing wrapping paper hide the edge of paper beyond the edge of the cutter after a section of the paper has been severed, and to get hold of the edge to pull on the paper to dis- 45 pense it from the roll it is necessary to manipulate the roll to force the paper edge ahead of the cutter. The paper edge often being ragged resists the movement and causes the paper coming from the roll to 50 buckle until the buckling force overcomes the resistance, when the ragged edge jumps past the cutter and curls about the roll. This brings the edge of the paper into a very 55 inconvenient place for gripping and time is lost. If the roller is turned to bring the

edge into a convenient position, it happens very often that the ragged edge passes inwardly beyond the cutter and it is necessary to raise the cutter and thread the paper, all of which causes delay and loss of time. 60

To obviate the above defects we have provided a cutter which has a limited movement and which is displaceable by the pull exerted on the paper when the same is fed off the roll, means being provided for restoring the cutter to its initial position and means for preventing the paper from returning when the cutter is returned, so that a portion of the paper from the roller always extends in front of the cutter, presenting 70 a gripping portion.

Referring to the drawings, 3 is a base of any suitable material, preferably rectangular in form. A standard 4 is mounted at each end of the base. Each of the standards 75 presents a bearing 5 for the axle 6 of a core 7 which carries a roll of paper 8. A block 9 is secured to each of the standards to engage frictionally the core 7 and thereby prevent a too easy rolling of the paper roll on 80 its bearings. Each of the standards has a rising rearwardly extending arm 10 which terminates in a curved bifurcated portion 11. A pair of feed rollers 12 have the axles 13 thereof engaged in the bifurcated portions 11. 85 The two rollers are maintained in contact by gravity.

A shield 14 extends from the axle 13 of the lower roller 12 over the paper roll 8. Its movement on the axle toward the roll 90 under the action of gravity is limited by arms 15 which engage the bifurcated portions 11 of the arms 10. A paper guide 16 is mounted to oscillate over the shield to and from the feed rollers 12, the axis of 95 oscillation being the axis of the paper roll 8. The paper 17 from between the feed rollers 12 passes over the guide 16. It is retained upon the guides by a retaining member 18 which is free to swing under the action of 100 gravity on the axle 13 of the upper feed roller 12. This retainer will prevent the paper from moving with the guide when the guide returns to its initial position under the action of counterweights 19 extending 105 from the bearings of the paper guide 16 toward the base 3. The counterweights normally tend to move the paper guide toward the feed rollers 12, the movement being limited by bumpers 20 which come in contact with ob- 110

2
structions formed in the base 3 for said bumpers. It will be noted that the counterweights are very close to the vertical plane passing through the axle 6 when the device is in normal position. In consequence an initial slight pull is required to start the movement of the guide. As soon as the movement of the counterweights is started it does not require very much pull to move them until the movement of the guide is arrested by the engagement of the bumper with the obstruction on the base, which limits the movement of the guide from the rollers. When the pull is released the weights are at about an angle of 15 45° with the vertical plane above referred to and, therefore, at maximum efficiency, thereby quickly bringing the guide to its initial or normal position.

A cutter 21 is provided above the guide 16 20 slightly rearward of the front, upwardly curved edge and secured to participate in the movement of the guide. Preferably sufficient clearance is provided between the guide and the cutter to facilitate an easy 25 threading of the paper between the two. The cutter 21 preferably forms a part of a shield or cover 22 which extends above the guide and houses the retainer 18. Normally a portion of the paper protrudes between the cutter and the guide, hanging over the guide so as to present an overhanging portion which can be easily gripped by the fingers. In pulling on the paper the guide is moved therewith until its movement is resisted by 30 the engagement of the bumper with the obstruction on the base, which determines the oscillation of the guide. In continuing the pulling, paper is drawn between the cutter and the guide until the desired amount of 35 paper has been drawn through. By a swift movement the paper can be severed at the cutter 21, particularly if the paper is narrow. In case of papers of great width, a finger is placed on to the shield 22 and the 40 paper can then be severed by a slow movement. In the first case, as soon as the paper has been severed gravity will restore the paper guide and, therefore, the cutter to the initial position, the return movement of the 45 paper being prevented by the retainer 18 and, in consequence, a portion of the paper will overhang the front end of the guide ready to be gripped. In the second case, as soon as the hold on the shield is released, 50 gravity will restore it to the initial position, leaving a portion of the paper protruding in the manner as stated.

The feed rollers 12 prevent a too rapid feed of paper when pull is exerted on the 55 paper or when paper is drawn off the roll. They further prevent the sagging of the paper between the guide and the roll. If by inadvertence the edge of the paper is beyond the cutter, it is only necessary to reverse the upper feed roller 12 in the direc-

tion of the arrow shown in Fig. 2, which would feed the paper past the cutter in the desired amount. Normally the amount of paper protruding ahead of the cutter depends on the amount of the angular displacement given to the paper guide. The member 14 forms a support for the paper for the time when the paper guide is in the displaced position and, therefore, prevents an accidental buckling of the paper between the 70 guide and the rollers when the guide is restored to its initial position. This member 14 also prevents the placing of too large a roll of paper upon the standards. It will be noted that the guide and shield associated 75 therewith are removable from the axle of the roller which protrudes through the standards 4, and that neither the retainer nor the paper support will interfere with the removal; the counterweights as well as 80 the bumpers being outside of the standards and diverging, in no way interfere with the removal of the guide. The feed rollers can be easily removed from the bifurcated portions 11 and therewith the member 14 and 90 the retainer to admit a new paper roll into the standards.

While we have described the principle of operation, together with the device which we now consider to be the best embodiment 95 thereof, we desire to have it understood that the device shown is merely illustrative and that such changes may be made as are within the scope of the appended claims.

We claim:

1. In a paper-roll rack, a revoluble core for a roll of paper, an arcuated paper guide mounted to oscillate in the axis of the core, feed rollers interposed between the guide and the core, means limiting the angular 105 displacement of the guide, said guide being displaceable by a pull exerted on the paper when feeding it off the core, a cutter on the guide, counterweights for returning the guide to its initial position, and a gravitationally-operable retainer adapted to engage the paper on the guide for preventing a retracting movement of the paper when the guide returns to its initial position.

2. In a paper-roll rack, a base for a roll 110 of paper, an arcuated paper guide mounted on the base to oscillate above the paper roll carried by the base, feed rollers adapted to be interposed between the guide and the roll of paper, bumpers carried by the guide 115 and adapted to engage the base for limiting the angular displacement of the guide, said guide being displaceable by a pull exerted on the paper to feed the paper off the roll, a cutter carried by the guide for severing the paper, counterweights associated with the guide for returning the same to its initial position after the pull on the paper is released, and a gravitationally-operable retainer adapted to engage the paper on the 120 125 130

guide for preventing a retracting movement of the paper when the guide returns to its initial position.

3. In a paper-roll rack, a revoluble core for a roll of paper, an arcuated paper guide mounted to oscillate in the axis of the core and adapted to present its convex surface to the paper from the roll, means normally resisting the oscillatory movement of the 5 guide, a cutter positioned above the guide and movable therewith, and a retainer adapted to engage the paper on the arcuated guide operable by gravity and preventing the return of the paper when the guide is returned 10 to its initial position.

4. In a paper-roll rack, a revoluble core for a roll of paper, an arcuated paper guide mounted to oscillate in the axis of the core, the radius of curvature of said arcuated 20 guide being greater than the distance of said guide from its axis of rotation, said guide being adapted to support the paper with its convex surface, means normally re-

sisting the oscillatory movement of the arcuated guide, a cutter carried by the guide in proximity of one of its straight edges, and a retainer adapted to be maintained by gravity on the convex surface of the guide for preventing a return movement of the 25 paper with the guide when the guide returns 30 to its initial position.

5. In a paper-roll rack, a revoluble core for a roll of paper, an arcuated paper guide mounted to oscillate in the axis of the core, said guide engaging the paper with its convex surface, said guide having a longitudinal concave depression near its forward straight edge, a cutter supported by the guide above said concave depression, and a retainer gravitationally maintained on the 35 convex surface of the guide for preventing the return of the paper when the guide is returned to its initial position.
